CLAIM

The ornamental design for a connector housing, as shown and described.

DESCRIPTION

FIG. 1 is a front elevation view of a connector housing, showing my new design;

FIG. 2 is a top plan view thereof;

FIG. 3 is a bottom plan view thereof;

FIG. 4 is a rear elevation view thereof;

FIG. 5 is a right side elevation view thereof;

FIG. 6 is a left side elevation view thereof;

FIG. 7 is a top, front and right side perspective view thereof;

FIG. 8 is a bottom, rear and left side perspective view thereof;

FIG. 9 is a front elevation view showing the lever in an open position;

FIG. 10 is a top plan view showing the lever in an open position;

FIG. 11 is a bottom plan view showing the lever in an open position;

FIG. 12 is a rear elevation view showing the lever in an open position;

FIG. 13 is a right side elevation view showing the lever in an open position;

FIG. 14 is a left side elevation view showing the lever in an open position;

FIG. 15 is a top, front and right side perspective view showing the lever in an open position; and,

FIG. 16 is a bottom, rear and left side perspective showing the lever in an open position.

The broken line portion of the figure drawings is included to show unclaimed subject matter only and forms no part of the claimed design.
